METHOD AND MEANS FOR ABRADING
LENSESKenneth C. Burroughs, Rochester, N. Y., assignor
to Bausch & Lomb Optical Company, Rochester, N. Y., a corporation of New York

Application October 9, 1935, Serial No. 44,247

6 Claims. (Cl. 51—278)

This invention relates to the lens grinding and polishing art wherein an abrading tool or lap is moved over the surface of a lens to grind or polish it.

5 The invention is an improvement over the invention disclosed and claimed in application Serial No. 433,934, filed March 7, 1930, by Carl E. Anderson for a Method and means for abrading lenses, now Patent No. 2,105,175, dated Jan. 10 11, 1938. It is quite difficult mechanically to locate the tool and lens of that application so that the edge of the tool passes exactly over the center of the lens. Unless the tool and lens are so located, the resultant lens will have either a raised 15 spot in the center due to insufficient abrading action, or will have a depressed spot due to double abrading action. The only alternatives disclosed by Anderson for preventing this difficulty, are the accurate positioning of the lens and tool 20 or the oscillating of the tool shaft and tool across the lens. Both of these obviously present mechanical difficulties.

One of the objects of the present invention is to provide a method and means for abrading 25 lenses wherein the tool will grind the lens uniformly and will be worn away in a substantially uniform manner over its entire area. Another object is to provide a method and means for abrading lenses wherein the tool is prevented 30 from grinding high or low target spots in the center of the lens. These and other objects and advantages reside in certain novel features of construction, arrangement and combination of parts and in my improved method, as will herein- 35 after be more fully set forth and pointed out in the appended claims.

Referring to the drawing:

Fig. 1 is a sectional view of an apparatus embodying my invention.

40 Fig. 2 is a schematic diagram illustrating the overlapping relation between the tool and the lens.

One embodiment of this invention is illustrated in the drawing wherein L indicates a lens blank 45 which is to be operated upon. The blank L is mounted, by any suitable means, upon a block or chuck 10 which is carried by a spindle 11 and adapted to be rotated through the application of suitable power to the pulley 12. A suitable 50 abrading tool or lap 13 is carried by the spindle 14 so that it may be rotated or driven by a belt or other means through the pulley 15.

The diameter of the abrading tool 13 is substantially equal to the diameter of the lens L so 55 that the area of the abrading surface is substan-

tially the same as the area of the surface of the lens to be ground or polished. The spindle 14 is inclined, as shown in Fig. 1, so that the tool 13 overlies the lens L with the center of rotation of the tool positioned substantially at the edge of 5 the lens L.

According to the present invention, the tool 13 is slightly eccentric on the shaft 14 and thus, during rotation, moves between the positions indicated at 13' and 13'' in Fig. 2. As stated above, 10 when the edge of the tool contacts the center of the lens, and the edge of the lens, the center of the tool, it requires great delicacy of adjustment to avoid grinding the center of the lens either twice or not at all. By making the tool eccentric on the shaft 14, the amount of abrading action at the center of the lens can be regulated. 15

It is also possible to obtain the same result by oscillating the shaft 14 about the center of curvature during the rotation of the tool. This system, 20 however, introduces difficulties of mechanical construction so that the eccentric positioning of the tool is preferable.

The lens L and tool 13 are rotated at the same speed in opposite directions, as indicated by the 25 arrows in Fig. 2, or they may be rotated in the same direction. The tool and lens being of substantially the same diameter and area and rotating at substantially the same speeds, the abrading action will be uniform over the entire surfaces of 30 the lens and tool. The tool will thus wear away uniformly without losing its curve so that a large number of lenses may be ground without the necessity for truing up the tool.

The fundamental principles underlying the 35 present invention are substantially the same as those underlying the invention disclosed in the above-mentioned application, Serial No. 433,934 filed March 7, 1930 by Carl E. Anderson, for a Method and means for abrading lenses. According to the present invention, however, the abrading tool is mounted eccentrically and the necessity of delicate or changing adjustments of the position of the tool, avoided.

From the foregoing it will be apparent that I 45 am able to attain the objects of my invention and provide improved method and means for abrading lenses wherein the tool will grind the lens uniformly and will be worn away in a substantially uniform manner over its entire area. 50 Various modifications can, of course, be made without departing from the spirit of my invention or the scope of the appended claims.

I claim:

1. A method of abrading lenses which com- 55

- prises rotating an abrading tool in contact with a lens having substantially the same diameter as the abrading surface of the tool, holding said tool eccentrically with its abrading surface 5 contacting said lens and with the center of rotation of the tool positioned substantially at the edge of the lens, and rotating said lens at substantially the same speed of rotation as the tool.
- 10 2. A method of abrading a lens having a substantially spherical surface which comprises placing in contact with said surface an abrading tool having a spherical surface which has substantially the same diameter and area as the surface 15 of the lens, rotating said lens about an axis concentric with said lens and rotating said tool at substantially the same speed as said lens about an axis eccentric to said tool, the axis of rotation of said tool lying substantially in a line passing through the edge of said lens.
- 15 3. Lens abrading apparatus comprising a lens carrying shaft, means for mounting a lens concentrically on said shaft, a tool carrying shaft positioned with its axis substantially at the edge 20 of said lens, a tool having substantially the same area and diameter as said lens, means for mounting said tool eccentrically on said tool carrying shaft, and means for rotating said two shafts at substantially the same speed.

4. Lens grinding means comprising a spindle carrying a block for supporting a lens, a second spindle mounted above the first spindle and in angular relation thereto, an abrading tool eccentrically fixed to said second spindle, said tool having a substantially continuous spherical surface whose area and diameter are substantially the same as the area and diameter of the lens, said tool being positioned in contact with the lens with its center of rotation substantially at 10 the edge of said lens and means for rotating said spindles at substantially the same speeds. 5

5. A method of abrading lenses which comprises placing a tool in contact with a lens, rotating said tool about an axis which is eccentric 15 to said tool and which passes adjacent the edge of said lens and rotating said lens at substantially the same speed as said tool.

6. A method of abrading lenses which comprises placing a tool in contact with a lens, rotating said tool about an axis which is eccentric to said tool and which passes adjacent the edge of said lens and rotating said lens at substantially the same speed as said tool about an axis which is concentric to said lens. 20 25

KENNETH C. BURROUGHS.
